UNITED STATES PATENT OFFICE.

ROBERT ELCOCK, OF JOHANNESBURG, TRANSVAAL, SOUTH AFRICA.

LOCK FOR CLOSURE CAPS.

Application filed July 7, 1921. Serial No. 482,937.

To all whom it may concern:

Be it known that I, ROBERT ELCOCK, a subject of the King of Great Britain, residing at Johannesburg, Transvaal Province of the 5 Union of South Africa, have invented certain new and useful Improvements in Locks for Closure Caps, of which the following is a specification.

The present invention has reference to 10 means for locking the closing caps or plugs of petrol tanks and other containers, and in connection therewith means for locking the outlet from the tank so that the contents of the same cannot be drawn off.

15 The invention is illustrated in the accompanying drawings, in which—

Fig. I is a vertical section showing one form of closure cap and a draw-off valve, the parts being locked.

20 Fig. II is a partial view similar to Fig. I showing the unlocked position of the part.

Fig. III is a section on A—A Fig. I.

Fig. IV is a section on B—B Fig. I.

25 Fig. V shows the invention applied to a push-in closure.

Fig. VI shows a further modification of the invention applied to a push-in closure, the device being unlocked and partly in section.

30 Fig. VII is a view of the same device as shown in Fig. VI but in the locked position.

Fig. VIII is a view of a locking ring showing pins and inclined grooves.

35 Figs. IX and X show a plan and elevation of a locking ring with cutting grooves.

1 indicates a petrol tank, and 2 the usual sleeve of the filling orifice of the same. 3 is a cap which screws onto said sleeve and which carries the locking mechanism.

40 The locking mechanism consists of means to prevent movement of the cap 3 relatively to the sleeve 2, means to render said last named means operative or inoperative and a permutation lock controlling movement of said second means.

45 In the construction illustrated in Fig. I, the cap 3 is prevented from rotating relative to the sleeve 2, and for this purpose a clutch device of the nature of a free-wheel mechanism is employed. This may consist for instance of a ring 4 mounted for rotation on the boss 5 formed on the cap. Inclined flats 6 on the ring form, with the inner surface of the sleeve, wedge slots 7 in which rollers 8 are carried, as by arms 9 pivoted to the ring at 10. Said rollers are urged towards the

narrow ends of the slots by springs 11 and the slots are so disposed that right handed rotation of the rings 4 with the cap,—to screw the latter up,—tends to move the rollers towards the wider end of their slots keeping them free from locking engagement with the sleeve; whilst rotation of the ring 4 in the opposite direction causes the rollers to jam the ring 4 fast with the sleeve 2.

The ring 4 and the boss 5 are made free for relative rotation to enable the ring 4 to remain stationary, whilst the cap 3 is unscrewed; and they are locked against rotation to lock the cap. For this purpose the ring 4 is provided with inward lugs 12 which enter an annular groove 13 in the boss 5. Stops 14 are arranged to slide vertically in slots 15 on the boss into or out of the groove 13, and when they are in said groove they engage the lugs 12 to hold the ring 4 from rotation on the boss.

Said stops 14 are formed on a yoke 16 connected to a central bolt 17 in such manner that the yoke and bolt move longitudinally 80 together whilst the bolt can rotate independently of the yoke. A spring 18 tends constantly to move the bolt upwards and said bolt is provided with an exposed head 19 for operating it.

85 The lock proper comprises a dial plate 20 which is mounted to rotate on the cap 3 and is marked with numbered divisions for determining its alternate movements to set the combination. A square neck 21 on the bolt 17 engages the dial plate to rotate the latter.

The combination elements consist of an outer fixed ring 21* and one or more rotatable rings of which two are shown and marked 22, 23. Said rings are provided with gate 95 apertures 24, which, when alined (or otherwise arranged with a predetermined relationship) permit a lug 25 extending from an arm 26 fast on the bolt 17 to pass into them, and thereby allow the bolt to move upwardly to 100 the extent necessary to move the stops 14 out of the groove 13 and clear of the ring lugs 12.

The combination rings are set by the lug 25 engaging a pin 27 on the ring 23 to rotate 105 the same, whilst a pin 28 on the inner ring 23 engages a lug 29 on the outer ring 22 to set the latter.

In order that the gates may not be found by rotating the bolt with the lug 25 in contact with the permutation rings, the outer fixed ring is provided as described in my

co-pending application Serial No. 474,539 filed June 2, 1921 with a number of false gates 30 into which the lug 25 tends to engage and from which it must be cleared by 5 pressing in the bolt before the latter can be rotated, so that when the bolt is free for rotation, the lug 25 is also clear of all the permutation rings.

The operation is as follows:—

- 10 The cap 3 can at any time be screwed down to close the tank, since the screwing down action tends to move the rollers 8 into the larger ends of the slots 7. Normally the bolt 17 is in its lowered position in which 15 position it holds the stops 14 in the groove 13 and locks the ring 4 relatively to the boss 5. Rotational movement of the cap to unscrew the same accordingly brings the rollers 8 towards the smaller ends of the slots 20 whereby said rollers jam and prevent further unscrewing of the cap. To release the cap it is necessary first to press down the bolt against the spring 18, then whilst the bolt is so held down, to rotate it to set the 25 combination elements, and finally to release the bolt and allow the lug 25 to enter the gates 24. The stops 14 then clear the lugs 12 of the ring 4 which latter can remain stationary relatively to the cap so allowing 30 the latter to be unscrewed.

For preventing the withdrawal of liquid from the tank there is provided any suitable valve or cock indicated by 31 which is actuated by a Bowden wire 32, 33. The sheath 32 of the Bowden wire is fixed to the bolt 17 so as to move longitudinally therewith, but not to rotate therewith. The core 33 is taken up through the bolt 17 and provided with a screwed head 34. Said head 34 is engaged by a nut 35 rotatively mounted in 40 the top of the bolt 17. Thus by rotating the nut 35 the valve 31 is opened or closed; but said valve is unaffected by movement of the bolt 17.

45 The nut 35 is locked against rotation relatively to the bolt 17 when the latter is down, and when therefore, the cap 3 is locked by a pin 36 sliding in the head 19 of the bolt 17 and projected against the top of the cap 3 by a spring 37. When the bolt 17 is down said pin passes into one of a series of holes 38 in the nut 35 to lock the latter. When the bolt 17 is raised the nut 35 is freed from the pin 36 and can be turned to open or 50 close the valve 31.

55 The modification illustrated in Fig. V is designed for locking a push-in closure, i. e., one which simply moves into or out of position without necessarily being rotated and 60 which can be of circular or any other cross sectional form. In this case the cap or plug 3 is provided with a number of wedge blocks 39 arranged around its circumference. Said wedge blocks are guided to move outwards 65 at an angle to the axis of the plug, and are

thrust outwards by springs 40. They are roughened at their ends 41 to grip upon the inner surface of the sleeve 2 and act when the plug is moved outwards to wedge between the plug and the sleeve, so stopping 70 such movement of the plug. A ring 42 is mounted on the plug to be movable axially thereon, and, when moved upwards to thrust in the wedge blocks 39. Said ring is thus moved upwards by the arms 16 on the bolt, 75 one of said arms carrying the ward 25. The longitudinal movement of the bolt 17 is controlled by the combination rings as before.

A further modification in which one or more split rings take the place of the wedge 80 blocks in Fig. V, is illustrated in Figs. VI and VII.

In this case the cap or plug 3 is plain and terminates at its lower end in a cylinder 43 of smaller diameter than the plug 3 and 85 containing the combination mechanism. On this cylinder are two rings 44 and 45 which are split as at 46 and have pins as at 52, 53, fixed at opposite ends of diameters, which work in grooves 48, 49 and 50, 51 in the 90 cylinder 43.

A ring 42 is mounted on a cap, 56 which corresponds to the arms 16 shown in Figs. I-V, but prevents the mechanism of the combination being seen in case the cap is 95 used for a glass bottle.

The cap 56 carries a ward 26 and is movable with the bolt longitudinally as hereinbefore described. The rings 44 and 45 are such that they are of the same, or slightly 100 less, diameter than the plug 3 when they are in their normal position as in Fig. VI.

The action of the device is as follows:—

In Fig. VII the closure is locked and the 105 ward 26 is therefore unable to enter the gates in the combination rings. Under these circumstances there is a comparatively large clearance between the plug 3, the rings 44, 45 and the ring 42. The spring 56 urges the rings 44 and 45 away 110 from the plug 3 and causes the grooves 48, 49 and 50, 51, working in conjunction with the pins 52, 53, and the pins corresponding to them on the other ring, to open the rings 45, 44 somewhat, thus forcing them into 115 contact with the interior face of the vessel itself.

If, now, an attempt be made to pull out the closure the rings are held stationary and the pins 52, 53 and the corresponding pins 120 on the other ring are forced down the grooves 48, 49 and 50, 51. Thus the more force is exerted to withdraw the closure the more force is exerted to expand the rings 125 and thus to retain the closure in the vessel.

When the closure is unlocked as shown in Fig. VI the ward 26 enters the gates in the combination rings, the ring 42 presses the rings 44, 45 against the plug 3 and the pins above referred to take up the position, 130

as shown in Fig. VI, relative to the rings, which latter then assume their normal position, there being no clearance between the cap 3, rings 44, 45 and ring 42. The closure can now be withdrawn.

If desired the rings 44, 45 can be roughened in order to assist the binding action or they can have grooves cut in them at opposite angles as shown in Fig. X so that, if an attempt be made to withdraw the closure by a twisting movement, this will have the effect of screwing the rings into the vessel.

Cutting edges on the grooves are provided at 57 and 58 only, so that only one set of grooves is in action at a time. It will be obvious that this form of closure can be utilized to close an orifice of any shape with slight modification.

20 I claim:

1. In combination, a receptacle, a closure therefor, movable members carried by the closure adapted to engage the receptacle with a wedging action upon outward movement 25 of the closure and means operable from the exterior of the closure for releasing the movable members from the cap and thus permit unscrewing action of the closure.

2. In combination, a receptacle, a screw 30 cap closure therefor, movable members carried by the cap adapted to engage the receptacle and cause a wedging action to prevent outward movement of the cap and a permutation lock carried by the closure and 35 adapted to be operated for releasing the movable member from the closure and thus permit unscrewing movement of said closure.

3. The combination with a receptacle and 40 a closure therefor, of movable members carried by the closure and adapted to engage the receptacle with a wedging action upon the outward movement of the closure, vertically movable means for controlling the 45 action of the said members, and a permutation lock controlled by said means.

4. The combination with a receptacle and a closure therefor, of a ring mounted on the closure to turn therewith and having wedge-shaped slots in its periphery, rollers in said 50 slots, means for locking said ring to the closure, and means for releasing said ring.

5. The combination with a receptacle and a closure adapted to be removed by rotating it, of a ring mounted on the closure to turn 55 therewith and having wedge shaped slots in its periphery, rollers in the slots, means for locking the ring stationary while the closure is being turned, and a permutation lock controlled by said means.

6. A closure adapted to be secured to and removed from a receptacle by a turning movement, said closure having a boss provided with an annular groove and vertical slots intersecting the groove, a ring surrounding the boss and provided with lugs entering said groove and with wedge-shaped slots on its periphery, rollers in said 65 slots, a sliding and spring pressed shaft mounted in the boss of the closure, and members carried by the shaft and projecting into the said slots and adapted to engage the lugs of the said ring.

7. A closure adapted to be secured to and removed from a receptacle by a turning 75 movement, said closure having a boss provided with an annular groove and with vertical slots intersecting the groove, a ring surrounding the boss and having lugs entering the groove and wedge-shape slots in 80 its periphery, rollers in the slots, a sliding and spring pressed shaft mounted in the boss and projecting through the same, a head on the upper end of the shaft, a yoke on the lower end of the shaft and having its members 85 extending into the slots of the boss and adapted to engage the lugs of the ring, and a permutation lock controlled by the movement of said shaft.

In testimony whereof I affix my signature. 90

ROBERT ELCOCK.
